[57] **CLAIM**

The ornamental design for a pull, as shown and described.

DESCRIPTION

FIG. 1 is a top perspective view of a pull showing the new design.

FIG. 2 is a top plan view of the design.

FIG. 3 is a front elevation view of the design. The rear elevation view is identical thereto.

FIG. 4 is a bottom plan view of the design; and,

FIG. 5 is a right side elevation view of the design. The left side elevation view is identical thereto.

The broken line disclosure in the FIGURES is for illustrative purposes only and forms no part of the claimed design.
